TUMBLER SWITCH

Otto Leuthold, Horgen, Switzerland

Application January 25, 1954, Serial No. 405,874

Claims priority, application Switzerland July 31, 1953

10 Claims. (Cl. 200—67)

The present invention relates to a tumbler switch which represents a further development of the tumbler switch according to the United States patent application, Serial No. 269,454, now abandoned, of which the instant application is a continuation-in-part, and incorporates a beam carried by at least one supporting member in a rocking bearing in which it can tilt, said beam serving to operate a switching rocker.

If such a switch is used for comparatively big switching capacities, especially in view of the heavy initial currents arising in the loading with tungsten lamps, it may happen that the contact elements weld together. Then the force of the spring otherwise causing the tilting of the switching rocker is no longer sufficient to open the contact. The primary object of the present invention is, therefore, to provide a tumbler switch in which the contact can be opened even if the contact elements may perchance be welded together.

The tumbler switch according to the present invention is essentially characterized in that the switching rocker has at least one actuating lug which projects into the path of motion of an associated cam of the beam and, upon actuation of the beam at least for opening said contact, comes up against the cam and then positively initiates movement of the switching rocker if the latter has not been previously tilted into its other switching position.

It is, therefore, another object of the present invention to provide means affording a simplified, yet highly efficient tumbler switch structure which may be easily and positively operated at all times, even when the contact elements thereof tend to adhere to one another.

It is still another object of the present invention to provide means conducive to novel and improved tumbler switches which are extremely sturdy and compact in construction but may be operated with a minimum of effort and with a minimum of noise.

A further object of the present invention is to provide means presenting effective and durable tumbler switches which are economically manufactured from a minimum number of parts, may be easily installed, and require no additional maintenance after installation.

Preferably, the design is such that the cam can only come up against the actuating lug when the beam has made more than half of the motion it requires for actuating the switch, i. e., when the beam has been pivoted past its dead center position. The beam may also include two cams which, when said beam moves in one way or the other, may cooperate with the actuating lug or lugs of the switching rocker in order to positively start tilting movement of the latter.

The invention will be fully and comprehensively understood from a consideration of the following detailed description when read in connection with the accompanying drawing which forms part of the application, with the understanding, however, that the improvement is capable of extended application and is not confined to

the exact showing of the drawing nor to the precise construction described and, therefore, such changes and modifications may be made therein as do not affect the spirit of the invention nor exceed the scope thereof as expressed in the appended claims.

In the drawing:

Fig. 1 is a side view of a tumbler switch according to the invention with closed contact, the insulating base being shown in section;

10 Fig. 2 is a sectional view of the tumbler switch embodying the invention, the view being taken along line II—II of Fig. 1;

Fig. 3 is a partial longitudinal sectional view of the same switch with opened contact, this view being taken 15 along line III—III of Fig. 2;

Fig. 3a shows a detail according to Fig. 3, and

Fig. 4 is a representation similar to Fig. 3 showing welded contact elements, and illustrating the opening motion and function of the operating beam.

20 Referring now more particularly to the drawing, the tumbler switch according to the invention comprises a base 10 of insulating material and has arranged thereon by means of screws 11 two fixing stirrups 12 adapted to hold a coverplate 13, the latter being indicated only in

25 chain-dotted lines in Fig. 1. Attached to base 10 by means of a screw 14 and nut 15 is a bearing member 16 adapted to carry a tiltable operating beam 17 and a switching rocker 18. For this purpose, bearing member 16 has two upright lugs substantially parallel to each other, 30 into each of which two V-shaped notches are cut from below and from above, respectively, which serve as rocking bearings of the knife-edge type. The operating beam 17 has two projections 19 which, as supporting members, engage in the upwardly opening bearing notches. From

35 Fig. 1 it may be seen that supporting members 19 at their free ends, and also the associated bearing notches, have cylindrical surfaces cooperating with each other and sliding on each other when beam 17 tilts. Each supporting member 19 is provided with a flange 20 which extends 40 past the associated bearing lug, preferably along the side thereof turned to the other bearing lug, thus preventing lateral displacement of operating beam 17 in the direction of its tilting axis. Beam 17, supporting members 19, and flanges 20 may, if desired, be formed from one 45 single piece of insulating material.

Switching rocker 18 engages with its shoulders 18a in the downwardly opening notches of bearing member 16 and is resiliently connected to beam 17 by tension spring 21. One end of said tension spring 21 engages a lug 50 or crossbar 22 of the switching rocker, said lug being provided with a concave knife-edge 22a, and the other end of the spring is attached to a cross-pin 23 of the beam. The spring is located between the two supporting members 19 and/or flanges 20 of the beam. The free end 55 of rocker 18 carries a contact element 24 which cooperates with a stationary contact element 25 seated on a leaf spring 26. For connecting the electric wires to the switch, provision is made for terminal screws 27 and 28, the first of them being connected to leaf spring 26, and the second of them by means of a connecting rail 29 to bearing member 16 and thus to rocker 18.

On each flange 20 there are provided two projections or cams 30 and 31 with a groove 32 formed therebetween, as more clearly shown in Fig. 4. Switching rocker 18 60 includes two actuating lugs 33, each of which extends into one of said grooves 32 and between which tension spring 21 is arranged. The width of groove 32 is, however, appreciably greater than the thickness of actuating lugs 33, so that each of these has a great amount of play 65 in its associated groove. From the above disclosure and from the drawing it may be realized that both actuating lugs 33 and also the associated cams 30 and 31 are

located in close proximity of the bearing centers of switching rocker 18 and/or of beam 17.

It will further be seen that the rocker 18 consists of a first portion extending rearwardly from the lugs 33 and shoulders 18a, e. g. the right-hand portion as seen in Fig. 1, and of a second portion bent over and forwardly from the rearmost point of said first portion of the rocker, whereby the contact element 24 is carried at the free and foremost end of said bent over rocker portion and thus is located substantially at the same level as the lower bearing surface of the bearing member 16 against which the shoulders 18a of the rocker 18 adjacent the lugs 33 abut.

Such an arrangement enables the switch assembly as an entity to be constructed with a minimum overall height, i. e., front to rear dimension, which is especially advantageous where the entire switch assembly is to be located exteriorly of the wall or other surface designed to support said switch assembly. Moreover, the arrangement of the rocker 18 makes it possible to locate the contact element 25 closer to the upper or front surface of the switch assembly, whereby access to the contact element 25 and to the associated terminal screw 27 for purposes of repair, adjustment and the like is greatly facilitated.

When operating beam 17 is tilted out of the position shown in Fig. 1 into that illustrated in Fig. 3, switching rocker 18 springs from the closed into the open position by action of tension spring 21. In the open position as in Fig. 3, the rocker abuts against a bent-over lug 34 (Fig. 2) of bearing member 16. If beam 17 swings in the other direction, rocker 18 again moves into the closed position as in Fig. 1, where the two contact elements 24 and 25 are engaging each other.

If contact elements 24 and 25 were to become welded together in consequence of a big initial current, the pull of spring 21 would not be sufficient to open the contacts when the beam is brought into the position shown in Fig. 3. But during the movement of the beam in the direction for opening contact 24/25, cam 30 of each flange 20 comes up against the associated actuating lug 33 of switching rocker 18, since said lugs project into the paths of motion of the cams. This position is shown in Fig. 4. If beam 17 is now pressed further in the direction of arrow P into the position as in Fig. 3, a torque in the sense of opening contact 24/25 will positively be exerted by cams 30 on actuating lugs 33. In this way the weld connection between contact elements 24 and 25 can be loosened and tilting movement of switching rocker 18 positively started, whereupon the pull of spring 21 suddenly moves the rocker into the open position.

It is understood that the tumbler switch could also be designed as a change-over switch by arranging a second leaf spring with a second stationary contact element in such a way that the contact element on the switching rocker engages said second stationary contact element on being tilted upwards. In this case lug 34, acting as stop, can be omitted. In the case of a change-over switch, it is possible that the switching rocker becomes firmly welded either when tilted downwards or upwards. If the latter is the case, upon actuation of beam 17 the cams 30 or 31 come up against actuating lugs 33 of rocker 18, whereupon the tilting movement of the switching rocker can be effected positively. The cams 30 and 31 are so arranged that they can only cooperate with the associated actuating lug 33 whenever the beam has passed through at least half of its movement required for operating the switch. Obviously, cams 30 and 31 only come up against the associated actuating lugs 33 of the switching rocker if the latter has not been previously tilted into the other switching position.

Alternatively, the tumbler switch could also be designed as intermediate switch or as two-pole switch. This needs two electrically separate, similar switching systems arranged parallel beside each other and operated by a common beam.

Should the switch according to the present invention be employed in a circuit where it would never be subjected to high currents or current surges, the cams 30/31 could be omitted. Finally, it would also be possible to provide only one single actuating lug cooperating with a single cam on the beam, or with two cams in the case of a change-over switch.

As compared with the switches described in the above-mentioned parent application, the switches disclosed hereinbefore have the advantage that any contact weldings perchance occurring cannot disable the action of the switch, and that the contact can always be positively opened.

Having thus described the invention, what is claimed as new and desired to be secured by Letters Patent, is:

1. A tumbler switch comprising a base of insulating material, an electrically conductive bearing member mounted on said base and having front and rear faces provided, respectively, with first and second bearing notches arranged opposite one another, an operating beam of insulating material provided with projection means engaging in said first bearing notches, whereby said beam is tiltably supported on said front face of said bearing member, a switching rocker provided with a first portion having front and rear ends and having shoulder means at said front end engaging in said second notches of said bearing member on the rear face thereof for rocking movement of said rocker relative to said bearing member, said rocker further being provided with a second portion extending forwardly of said base from said rear end of said first portion and having a first contact element fixed thereto at the foremost part of said second portion, resilient means connected at one end to said operating beam and at another end to said switching rocker adjacent the junction of said first and second portions and operable to retain both said beam and said rocker on said bearing member, at least one pair of cams on said beam, said cams being spaced from one another in a direction transverse to the tilting axis of said beam to form a recess, at least one actuating lug on said first portion of said rocker and projecting into said recess, and a second contact element stationarily mounted on said base and engageable by said first contact element, whereby said resilient means alone normally causes said rocker to be rocked upon tilting movement of said beam, said cams being operable to engage said actuating lug and initiate rocking movement of said rocker only upon failure of said resilient means to initiate said rocking movement.

2. A tumbler switch comprising a base of insulating material, a bearing member on said base and having front and rear surfaces, operating means of insulating material supported on said front surface of said bearing member for rocking movement about a first axis, a switching rocker comprising first and second portions arranged at an acute angle with respect to one another with one end of said first portion being in contact with said rear surface of said bearing member for rocking movement of said rocker about a second axis substantially parallel to said first axis, a contact element on that end of said second portion of said rocker remote from said one end of said first portion and movable therewith, the lengths of said first and second portions being predetermined to dispose said movable contact element in substantially coplanar relationship with said rear surface of said bearing member, resilient means connected to both said operating means and said switching rocker and biasing both said operating means and said rocker against said front and rear surfaces of said bearing member, cam means on said operating means, actuating means on said rocker and projecting into the path of movement of said cam means, and a stationary contact element on said base and engageable by said movable contact element, said resilient means alone normally being operable to rock said rocker about said second axis upon rocking movement of said operating means about said first axis, said

cam means when moving in said path being operable to apply force to said actuating means and initiate rocking movement of said rocker only upon failure of said resilient means to initiate said rocking movement due to binding of said contact elements.

3. In a tumbler switch having a base of insulating material and a fixed contact element thereon; the combination of a bearing member on said base and having front and rear surfaces, at least said rear surface of said bearing member being electrically conductive, with operating means pivotally engaging said front surface of said bearing member, electrically conductive rocker means engaging said rear surface of said bearing member for rocking movement relative thereto about an axis parallel to the axis of pivotal movement of said operating means, a movable contact element connected to said rocker means at a location substantially coplanar with said rear surface of said bearing member and engageable with said fixed contact element in one position of said rocker means, spring means connected to both said operating means and said rocker means and biasing both the latter and said operating means into engagement with said front and rear surfaces of said bearing member, respectively, said spring means alone normally being operable to impart rocking movement to said rocker means upon pivotal movement of said operating means on said bearing member, and cooperable means on said operating means and on said rocker means and adapted to abut one against the other only upon failure of said spring means to cause said rocking movement due to binding of said contact elements, thereby applying positive contact opening forces to said rocker means.

4. The combination according to claim 3, said co-operable means comprising cam means on said operating means and actuating means on said rocker means, said actuating means being disposed within the path of movement of said cam means.

5. The combination according to claim 3, said co-operable means comprising cam members on said operating means spaced from one another substantially transversely of said axis of pivotal movement of said operating means and defining a recess, and at least one actuating lug on said rocker means projecting into said recess.

6. The combination according to claim 3, said co-operable means comprising at least two cam members on said operating means and spaced from one another in a direction substantially parallel to said axis of pivotal

movement of said operating means, and at least two actuating lugs on said rocker means, said lugs projecting, respectively, into the paths of movement of said cam members as said operating means moves from its closed-contact position to its open-contact position.

7. The combination according to claim 6, said spring means having one portion connected to said operating means intermediate said cam members and having another portion connected to said rocker means intermediate said actuating lugs.

10 said said actuating lugs.

8. The combination according to claim 6, said cam members being located in close proximity to said axis of pivotal movement of said operating means, and said actuating lugs being located in close proximity to the

15 rocking axis of said rocker means.

13 rocking axis of said rocker means.
9. The combination according to claim 6, said co-
operable means further comprising two additional cam
members on said operating means, said additional cam
members being spaced from one another in a direction
20 substantially parallel to said axis of pivotal movement of
said operating means and being spaced from said first-
named cam members, respectively, in a direction sub-
stantially transverse to said axis of pivotal movement
of said operating means, whereby a recess is defined be-
25 tween each of said first-named cam members and the
corresponding one of said additional cam members, said
lugs projecting into said recesses, respectively.

legs projecting into said recesses, respectively.

10. The combination according to claim 9, said rocker means comprising first and second portions extending substantially lengthwise of one another and each having opposite front and rear ends, said front end of said first portion engaging said rear surface of said bearing member, said rear end of said first portion being joined to said rear end of said second portion, said movable contact element being connected to said front end of said second portion, and the length of said second portion being predetermined to dispose said movable contact element in substantially coplanar relationship with said rear surface of said bearing member.
